UNITED STATES PATENT OFFICE.

JAMES ROBERT BROWN, OF HALLS, TENNESSEE.

DEMOUNTABLE RIM.

1,357,144.

Specification of Letters Patent. Patented Oct. 26, 1920.

Application filed November 17, 1919. Serial No. 338,507.

To all whom it may concern:

Be it known that I, JAMES ROBERT BROWN, a citizen of the United States, residing at Halls, in the county of Lauderdale and State 5 of Tennessee, have invented certain new and useful Improvements in Demountable Rims; and I do hereby declare the following to be a full, clear, and exact description of the invention, such as will enable others skilled 10 in the art to which it appertains to make and use the same.

The present invention relates to improvements in demountable rims for vehicle wheels, and the primary object thereof is to 15 provide an improved rim and coöperating wheel structure that admits of the rim being readily and quickly detached from the wheel without the use of special tools, to the end that rapid changes of tires may be made 20 by motorists on the road.

Another object of the present invention is to provide an improved demountable rim in which an improved locking device is employed for holding the rim on the wheel 25 body, and which admits of easy operation to free the rim when occasion demands.

In the accompanying drawings forming a part of this application, and in which similar reference symbols indicate corresponding parts in the several views:

Figure 1 shows an elevational view, with parts in section, of an improved wheel constructed in accordance with the present invention and shown in one position.

Fig. 2 is a similar view showing the parts in the locked position.

Fig. 3 shows a view of the wheel, partly broken away and with the demountable rim removed.

Fig. 4 shows an edge view of the improved felly band.

Fig. 5 is an elevational view, partly in section, of the improved demountable rim, and

Fig. 6 is a sectional view taken on the line 6—6 in Fig. 5.

Referring more particularly to the drawings, 1 designates the hub, from which radiate the spokes 2, and 3 represents the wooden felly carried on the outer ends of the spokes 2.

On the felly, I provide a felly band 4, preferably of metal, in which are produced a plurality of circumferentially extending

slots 5 provided in connection with transverse slots 6 that open through one side of the felly band 4 and communicate with the slots 5 at one end thereof. The two slots 5 and 6 together form a bayonet-like slot. The felly band 4 is further provided with an 60 elongated slot 7 which registers with a similar slot 8 in the felly 3 for the purpose of receiving the valve stem of the tire as further referred to.

A portion of the felly 3 is cut away as indicated at 9 in Fig. 3, to provide a recess in which is seated the shank 10 of a locking dog 11, which latter projects out through a slot 12 in the felly band 4. A bolt or pin 13 passes through the felly band 4 and 70 loosely engages the shank 10, so as to provide a pivot on which the dog 11 may move radially.

A coil spring 14 is arranged in a socket 15 beneath the dog 11 and acts to yieldingly 75 hold the dog in the projected position shown in Figs. 2 and 3, while allowing the dog 11 to be depressed as shown in Fig. 1, for the purpose of allowing the demountable rim to move into and out of the locked position on 80 the wheel. A stem or rod 16 is connected to the dog 11, passes through the convolutions of the spring 15 and through the felly 3, and provides an elongated handle which may be grasped to draw the dog 11 inwardly. 85 As best shown in Fig. 4, the outer edge of the dog 11 is formed with a semi-cylindrical depression 17, which corresponds substantially to the form of a locking stud 18 carried on the interior of the demountable 90 rim 19.

The rim 19 is further provided with a series of bosses 20 extending radially inward from substantially the central portion of the rim, and these bosses are provided 95 to engage through the slots 6 and 5 in the felly band 4, as indicated in Figs. 1 and 2. A perforation 21 in the demountable rim 19 is provided to admit the valve stem which passes through the slots 7 and 8, respectively, 100 in the felly band 4 and felly 3, the slots being elongated to allow of the movement of the valve stem when the demountable rim 19 is rotated on the felly band as required to shift the bosses 20 into the closed ends of 105 the slots 5. In this latter condition the parts are shown in Fig. 2.

Referring to Fig. 6, the demountable rim

19 is provided with a fixed flange 22 and a removable flange 23 which is a split ring, the divided ends of which are indicated at 24 in Fig. 5. This removable flange 23 is formed with an inner shoulder 25 having an outwardly beveled outer face 26 adapted to come in contact with a correspondingly formed beveled face 27 provided in a socket 28 at the side of the demountable rim 19. 5 The effect of this arrangement is to allow of the springing of the open ends 24 of the flange 23 apart to permit ready removal of the flange and quick application of the flange to the rim 19; and without the use 10 of any locked parts, but due solely to the pressure exerted when the tire is inflated and expands laterally, the flange 23 will be shifted outwardly, causing the beveled faces 26 and 27 to ride into contact, and this will be attended by a contraction of the flange 23, so that the greater the pressure the tighter will the flange 23 grip the demountable rim. 15

In practice the demountable rim 19 such 20 as shown in Fig. 5, but having a tire thereon, which has been removed and not shown for purposes of clearer illustration, is applied to the wheel by first bringing the locking bosses 20 into registry with the transverse slots 6 in the felly band 4, whereupon the demountable rim 19 is moved axially of the wheel until the bosses 20 arrive in the open ends of the slots 5. Thereupon the demountable rim 19 is rotated upon the 25 felly band 4 in the direction to cause the bosses 20 to move into the closed ends of the slots 5. The valve stem extending through the opening 7 is first fitted through the slot 8 in the felly. 30

40 The locking stud 18 will, in consequence of this movement, rotate over and depress the locking dog 11, as shown in Fig. 1, and when the parts are shifted to the final position such stud 18 will have found a seating in the slot 12, where it will be held from escape by the dog 11. In this condition the parts are locked against accidental displacement and can only be moved when the dog 11 is released by exerting a radially 45 inward pull upon the rod 16. 50

In view of the foregoing it will be apparent that I have provided an improved demountable rim capable of quick detachment and application to the wheels of automobiles or other vehicles, and which when 55

locked in place will be held securely against accidental displacement, and moreover the improved flange on the demountable rim may be easily operated and forms an effectual lock in actual practice. 60

It is obvious that those skilled in the art may vary the details of construction and arrangements of parts without departing from the spirit of my invention, and therefore I do not wish to be limited to such features 65 except as may be required by the claims.

I claim:

1. In combination with a wheel body, a felly band carried thereby and having angled slots therein opening through one edge 70 of the band, said felly band also having a locking slot therein, said wheel body having a socket beneath the locking slot, and a cut away portion extending in one direction from said socket, a locking dog mounted for radial movement in said locking slot and having a shank projecting into said cut away portion, means extending into the cut away portion for loosely pivoting said shank, a spring in said socket for urging 80 said dog outwardly, a pin connected to said dog and passing through said socket for drawing the dog inwardly, and a demountable rim having bosses adapted to enter said angled slots and also having a locking stud 85 adapted to enter said locking slot and be held therein by said dog, substantially as described.

2. In combination with a wheel body, a felly band carried thereby and having a locking slot therein, said wheel body having a socket beneath the locking slot, and a cut-away portion extending in one direction from said socket, a locking dog mounted for movement in said locking slot and 90 having a shank projecting into said cut-away portion, means extending into the cut-away portion for loosely pivoting said shank, a spring in said socket for urging said dog outwardly, means connected to 100 said dog whereby the latter may be drawn inwardly, a demountable rim adapted to be fitted over said felly band and having a locking stud adapted to enter said locking slot and be held therein by said dog, and 105 means operable by relative circumferential movement to secure the rim and wheel together, substantially as described.

JAMES ROBERT BROWN.
